(57) **CLAIM**

The ornamental design for a secondary package for contact lens blister packaging, as shown and described.

DESCRIPTION

FIG. 1 is a perspective view of a secondary package for contact lens blister packaging showing the new design; FIG. 2 is a side view of the secondary package for contact lens blister packaging of FIG. 1; FIG. 3 is a front view of the secondary package for contact lens blister packaging of FIG. 1; FIG. 4 is a top view of the secondary package for contact lens blister packaging of FIG. 1; FIG. 5 is a bottom view of the secondary package for contact lens blister packaging of FIG. 1; and, FIG. 6 is an exploded perspective view of the secondary package for contact lens blister packaging of FIG. 1. The broken lines shown represent portions of the secondary package for contact lens blister packaging that form no part of the claimed design.
